FIGURE 1 is a side elevational view of a convertible table, bench, bed platform and chest unit, showing my new design, illustrated in its table position;

FIGURE 2 is an end elevational view thereof in the position of FIGURE 1;

FIGURE 3 is a perspective view thereof, illustrated in a combination table and bench position, with a lid of a chest portion illustrated in its open position;

FIGURE 4 is a reduced scale side elevational view thereof in the position of FIGURE 3 except both chest lids are closed.

FIGURE 5 is a reduced scale end elevational view thereof as seen from the left in FIGURE 4.

FIGURE 6 is a reduced scale top plan view thereof, in the position of FIGURE 3;

FIGURE 7 is a reduced scale side elevational view thereof, illustrated in the dual bench position;

FIGURE 8 is a perspective view thereof, illustrated in the bed platform position; and

FIGURE 9 is a reduced scale side elevational view thereof in the position of FIGURE 8, showing the lids of the chest units in open positions.

The dominant features of my design reside in those portions shown in full lines on the drawing.

I claim:

The ornamental design for a convertible table, bench, bed platform and chest unit, substantially as shown and described.
